UNITED STATES PATENT OFFICE.

LEE E. MITCHELL, OF BOSTON, MASSACHUSETTS.

HYDRAULIC AIR-COMPRESSOR.

SPECIFICATION forming part of Letters Patent No. 641,981, dated January 23, 1900.

Application filed July 13, 1899. Serial No. 723,690. (No model.)

To all whom it may concern:

Be it known that I, LEE E. MITCHELL, of Boston, in the county of Suffolk and State of Massachusetts, have invented a new and Improved 5 Hydraulic Air-Compressor, of which the following is a full, clear, and exact description.

My invention relates to an improvement in air-compressors actuated by means of a hydraulic cylinder and comprises the novel features hereinafter described and claimed.

Reference is to be had to the accompanying drawings, forming a part of this specification, in which similar characters of reference indicate corresponding parts in all the figures.

15 Figure 1 is a side elevation of my device complete, showing the water and air cylinders. Fig. 2 is a sectional side elevation of the same. Fig. 3 is a sectional side elevation of the lower portion of the hydraulic cylinder, 20 showing the valve-reversing piston and the valves by which it is controlled. Fig. 4 is a similar sectional elevation showing the valves in different positions. Fig. 5 is a sectional side elevation of the lower portion of the hydraulic cylinder, showing the water inlet and 25 discharge valves and the piston by which they are actuated. Fig. 6 is a similar elevation showing the parts in a different position. Fig. 7 is a sectional plan taken upon the line 7 7 30 in Fig. 3. Fig. 8 is a sectional plan taken upon the line 8 8 in Fig. 5, and Fig. 9 is a sectional side elevation of the pipes and valves connecting the opposite ends of the air-cylinder.

35 The principal object of my invention is to produce a hydraulic cylinder and its valve mechanisms which are automatically operated, so that the piston will continue reciprocation until shut off by some outside means, 40 said device being especially adapted for use in compressing air. It is, however, evident that the hydraulic cylinder and its mechanisms may be used for any form of power purposes, the compressing of air being only one of many uses to which it may be put.

45 While the device is described as used in connection with an air-compressor, it is to be understood that the hydraulic portion of the device may be used for any power purpose.

50 The power portion of the device herein shown consists of a cylinder A, having a piston a therein, and the valve mechanisms

which are located at the lower end of the cylinder, the same being contained within a section B, which is preferably screw-threaded to 55 the lower end of the cylinder A, the joint between the two being made tight by means of a packing-ring a³. To the lower end of the section B is screw-threaded the base C, which has a chamber I therein, serving to receive the 60 water which passes to and from the opposite end of the power-cylinder A, said chamber being connected with one end of a pipe I', said pipe being connected to the upper and lower ends of the power device by means of unions 65 I² and short nipples, which connect, respectively, with the chamber I and the upper end of the cylinder A.

When the device is used as an air-compressor, the piston a will have a hollow piston-rod a', which passes through a stuffing-box a⁴ into the air-compressing cylinder A', where it is connected with the air-compressing piston a². The admission and discharge of air to and from the air-compressing cylinder 75 A' are controlled by means of check-valves K', k, K², and K³, connected, respectively, to opposite ends of the cylinder by means of nipples K⁴ and K⁵ and connected with each other by means of a pipe K. This mechanism is 80 only one of many forms which may be used for this purpose, and as it does not form any essential part of my present invention will not be described in further detail. Said mechanism is of such a character as to freely 85 admit air to opposite ends of the cylinder through the check-valves k and K³ and to discharge the same through the check-valves K' and K².

The section B, which contains the valve 90 mechanism for controlling the admission and discharge of water, has two end diaphragms or partitions B' and B² and a central vertical partition B³, which divides the section B into two chambers S and W, said chambers being 95 respectively the supply and waste-water or discharge chambers. The vertical partition B³ is swelled in the center, so as to form a cylinder B⁴, which contains a piston D, by which the main water admission and discharge valves are actuated. In the upper diaphragm B' are formed two apertures leading, respectively, into the supply and waste-water chambers and adapted to receive plugs E

E², which form valve-seats and passages for the water. These plugs have a hollow center, through which pass the water and the valve-stems d² d². The lower end of the upper plug E is faced off, so as to form a valve-seat which acts in connection with the valve d⁶, said valve being provided with a leather or similar facing washer d'. The upper end of the upper plug E or the end which projects within the cylinder has a diaphragm E', closing the same, said diaphragm being provided with a hole which is concentric with the hole in the plug through which the water passes, said hole in the diaphragm E' acting as a guide for the rod or stem d⁵, to which the valve d⁶ is secured. The water is discharged from the main passage in the plug E through lateral passages e, which communicate therewith and with the interior of the cylinder A. The plug E is the one through which the water passes when admitted from the supply-chamber S to the cylinder A. The plug E², which is upon the opposite side of the cylinder, is somewhat similar in construction, but is reversed in position, and, together with the valve d, controls the discharge of the water from the cylinder A. This plug E² has a central water passage, a diaphragm E², which in this case is on the lower end of the plug or that end which projects into the waste-water chamber W, and it is provided with lateral passages e' for the discharge of water. These plugs are preferably threaded, so as to screw into the openings in the diaphragms B' B². The upper ends of both plugs are of slightly greater diameter than the threaded portion, so as to form a stop limiting the downward motion of the plugs when screwed to place.

The valve d, which controls the discharge of water from one end of the cylinder, is similar in construction to the valve d⁶ and provided with a leather or similar washer d', which directly engages the valve-seat. This valve is mounted upon a stem or rod d², said stem and the stem d⁵ being connected with a cross head or bar D², so that both stems are moved together.

The two valves just described control the admission and discharge of water to and from one end only of the cylinder. Similar valves d⁷ and d⁸ are provided for controlling the admission and discharge of water to and from the opposite end of the cylinder. These valves are, however, placed in the lower diaphragm B². The plugs E and E², which form the seats for the lower valves, are exactly the same in construction as the corresponding plugs placed in the upper diaphragm B'. These water-controlling valves are actuated by means of the piston D, which is mounted within the cylinder B⁴, located concentric with the power-cylinder A. The lower end of the cylinder B⁴ is closed by a screw-threaded plug b' and the upper end by a plug b, which is also provided with a central hole for the piston-rod D' and with a suitable packing means for said piston-rod.

The water is admitted to and discharged from the cylinder B⁴ through ports f³ f⁴ and g³ g⁴, located in opposite ends and upon opposite sides of the cylinder. These ports are controlled by means of valve-cylinders F and G, which contain piston-valves, two piston-valves being provided for each of the cylinders, the cylinder F containing piston-valves F' and F² and the cylinder G containing piston-valves G' G³, each of the valves in said cylinders controlling the port in its respective end of the cylinder B⁴. Each of the valve-cylinders F and G is provided with a central cut or notch F⁴ and G⁴, respectively, which permits communication between the valve-cylinders and the supply and waste-water chambers, respectively.

The pistons G' and G³, which control the admission of water to the cylinder B⁴, are both mounted upon a common rod or stem G², and the piston-valves F' and F², which control the discharge of water from the cylinder B⁴, are mounted upon a common rod or stem F³, both of these rods being connected with a cross head or bar H, so that all of the piston-valves will move together. The valves are directly actuated by the reciprocation of the power-piston a. The cross-head H has a rod H' centrally connected thereto and extending within the hollow piston-rod a'. The rod H' has a nut or collar h secured to its upper end and forming a tappet, said nut or collar being of such a size as to slide freely in the bore of the rod a', but being larger than the aperture in the piston a, through which the rod H' reciprocates. The piston a in its downward travel will ultimately strike the cross-head H and move it downward, carrying the piston-valves with it. In its upward movement the piston will ultimately strike the collar or tappet h and carry the rod H' and cross-head H, together with the piston-valves, upward. These two movements are relied upon to move said valves, so as to admit and discharge water to and from opposite ends of the cylinder B⁴, containing the valve-shifting piston.

The valve-cylinder G, through which water is admitted to the valve-shifting cylinder, is provided with longitudinally-extending grooves g, (clearly shown in Figs. 3, 4, and 7), said grooves extending from the central notch G⁴ a part only of the distance to the ports g³ and g⁴. When either of the piston-valves G' and G³ is so placed that it overlaps these longitudinal grooves, as is the case with the piston-valve G' in Fig. 4, water can escape from the supply-chamber S through these ports to the opposite side of the piston-valve, thus permitting, in the position shown in Fig. 4, the water to be admitted to the upper end of the valve-shifting cylinder B⁴, thus causing the piston D therein to be forced downward. If the valves are shifted to the opposite position or that shown in Fig. 3, the supply-chamber S would be brought into communication with the lower end of the cylinder B⁴, thus

forcing the piston D upward. The water is discharged through the valve-cylinder F, and in this cylinder the longitudinal grooves f, which are similar in construction to the 5 grooves g in the other valve-cylinder, are placed at the ends of the cylinder and communicate with the ports f³ and f⁴. In the position shown in Fig. 3 water is being admitted to the lower side of the piston D and 10 being discharged from the upper side thereof. In the position shown in Fig. 4 water is being admitted above the piston D and discharged from beneath the same. The operation of the device is as follows: In the position 15 of the parts shown in Fig. 4 water is being admitted to the upper side of the piston D, which forces the same downward and forces downward the water-controlling valves d⁶, d⁷, d, and d⁸. This closes the water-discharge 20 valve d from the lower end of the cylinder and opens the water-discharge valve d⁸ connected with the upper end of the cylinder. It also opens the water-supply valve d⁶ connected with the lower end of the cylinder and 25 closes the water-supply valve d⁷ connected with the upper end of the cylinder. The water-supply is thus admitted to the lower end of the cylinder and discharged from the upper end, forcing the piston a upward. When 30 the piston a reaches the upper limit of its travel, it strikes the washer or tappet h, pulling upward the cross-head H, thus shifting the piston-valves from the position shown in Fig. 4 to that shown in Fig. 3. This 35 reverses the direction of flow of the water through the cylinders F and G, admitting the supply through the port g⁴ to the lower end of the cylinder B⁴ and discharging the water at the upper portion of the same piston through 40 the port f³ into the waste-water chamber. This causes the piston D to rise, carrying the water-controlling valves with it, thus reversing their position to that shown in Fig. 5 and discharging the water from the lower end 45 of the cylinder A and admitting the water through the chamber I and pipe I' to the upper end of the cylinder A. This device will continue in the same order of operations until the water-supply is cut off or the air-pressure 50 sure becomes sufficient to prevent its motion.

This device is adapted to a wide range of work, as the relative area of the water and air cylinders may be varied and made such as desired. It is thus possible to use water 55 of high pressure economically for producing compressed air of low pressure or to use water of low pressure to produce compressed air of high pressure.

Having thus fully described my invention, 60 I claim as new and desire to secure by Letters Patent—

1. A hydraulic pumping-cylinder, having in one end supply and waste-water chambers provided oppositely with ports communicating 65 with opposite ends of the power-cylinder, connected supply and waste-water valves adapted to control the flow of water through

said ports to and from the power-cylinder, a shifting cylinder having a piston connected with said valves, a plurality of valve-chambers alongside of and parallel with the shifting cylinder, shifting valves movable in said chambers and controlling the shifting piston and tappet connections for moving said shifting valves from the power-piston at each end 70 of its stroke, substantially as described. 75

2. A hydraulic pumping-cylinder having in one end supply and waste-water chambers provided oppositely with ports communicating with opposite ends of the power-cylinder, 80 connected supply and waste valves adapted to control the flow of water through said ports, a shifting cylinder having a piston connected with said valves, valve-cylinders located alongside the shifting cylinder and connected therewith, shifting valves in said cylinders movable parallel with the power-piston to control the shifting piston, a hollow rod for the power-piston, a rod slidably in said hollow rod, means whereby said rod is moved by 90 the power-piston at each end of its stroke, and connections from the rod to the shifting valves, substantially as described.

3. A hydraulic pumping-cylinder, having in one end supply and waste-water chambers provided oppositely with ports communicating with opposite ends of the power-cylinder, 95 connected supply and waste valves adapted to control the flow of water through said ports, a shifting cylinder having a piston connected with said valves, two valve-cylinders lying alongside the shifting cylinder and connected therewith by ports at their ends, one of said cylinders and its valves controlling the water-supply to the shifting cylinder, and 100 the other controlling the waste-water discharge therefrom, said valve-cylinders having respectively a supply and waste connection with their central portions, the supply-cylinder having longitudinal grooves or ports 105 in its central portion communicating with its supply-opening and the waste or discharge cylinder having similar grooves or ports within each end connecting with the ports leading from the shifting cylinder, two connected piston-valves in each cylinder adapted 110 when reciprocated to alternately uncover the longitudinal ports or grooves, and means for moving them from the power-piston, substantially as described.

4. In a hydraulic power-cylinder, a valve-shifting cylinder and piston and valve mechanism controlling the shifting piston, comprising two valve-cylinders lying alongside of the shifting cylinder and communicating 115 therewith by ports at each end, said valve-cylinders having respectively a supply and a waste-water connection with the central portion thereof, and longitudinal grooves or ports lying respectively in the central portion of 120 the supply-cylinder and communicating with the supply-opening thereof and at the ends of the waste-cylinder and communicating with the shifting-cylinder ports, and two con-

nected piston-valves in each cylinder adapted when reciprocated to uncover diagonally opposite grooves, and externally-operated means for shifting said valves, substantially as described.

5. A hydraulic power cylinder and piston, the cylinder having at one end a section having a longitudinally-extending partition forming supply and waste-water chambers, and 10 provided with a central circular chamber forming a shifting cylinder, the supply and waste-water chambers having ports at one end connecting directly with one end of the power-cylinder and at the other end communicating 15 by a pipe with the other end of the power-cylinder, valves controlling said ports, a piston in the shifting cylinder and connected with said valves, auxiliary or shifting valves controlling the shifting piston and connections 20 whereby said valves are adapted to be operated by the power-piston, substantially as described.

6. A hydraulic pumping-cylinder having in one end supply and waste-water chambers 25 each provided with ports communicating respectively with opposite ends of the cylinder, supply and waste-water valves controlling said ports, a shifting cylinder, a piston in said cylinder a cross-head carried at the upper 30 free end of the shifting piston-rod, the stems of said supply and exhaust valves being connected with the cross-head, shifting valves controlling the shifting piston, and connections whereby said shifting valves are moved 35 from the power-piston at each end of its stroke, substantially as described.

7. A hydraulic pumping-cylinder provided with a power-piston having a hollow piston-rod, the said cylinder having in one end supply and waste-water chambers provided oppositely with ports communicating with opposite ends of the power-cylinder, connected 40 supply and waste-water valves adapted to control the flow of water through said ports to and from the power-cylinder, a shifting cylinder having a piston connected with said valves, shifting valves movable at opposite sides of the shifting cylinder and controlling the shifting piston, a cross-head connecting 45 the stems of the shifting valves and a rod connected with the cross-head and adapted to

slide in the hollow rod of the power-piston, the movement of said rod and the parts connected therewith being controlled by the movement of the power-piston, substantially 55 as described.

8. The combination with a hydraulic cylinder having in one end supply and waste-water chambers provided oppositely with ports communicating with opposite ends of the power-cylinder, of connected supply and waste-water valves adapted to control the flow of water through said ports, a shifting cylinder having a piston connected with said valves, shifting valves movable alongside of 60 and parallel with said shifting cylinder and controlling the shifting piston, a hollow rod for the power-piston, an air-compressing cylinder into which said hollow rod extends, the said rod carrying the air-compressing piston, 65 a rod slidable in said hollow rod, and provided at its ends with means adapted to be engaged by the power-piston at each end of its stroke, and a cross-head carried by said rod and connected with the stems of the shifting valves, substantially as described.

9. In a hydraulic power-cylinder, a supply and a waste-water chamber in one end of said cylinder, each chamber being provided with a port at each end having a valve-seat, the 80 ports at opposite ends of the chambers communicating with opposite ends of the power-cylinder, the valve-seats for the ports of one of said chambers being located within the chamber and facing each other, and the valve-seats for the ports of the other chamber being located at the outside of the chamber, and facing in opposite directions, a valve for each port the said valves being adapted to control the flow of water through said ports to and from the power-cylinder, a chamber between the supply and waste-water chambers, the said chamber forming a shifting cylinder, a piston in said shifting cylinder and connected with the said valves, and means for controlling the shifting piston, substantially as described.
